Patented May 21, 1918.

UNITED STATES PATENT OFFICE.

ROBERT W. SCOTT, OF BOSTON, MASSACHUSETTS, ASSIGNOR, BY MESNE ASSIGNMENTS,
TO SCOTT & WILLIAMS, INCORPORATED, A CORPORATION OF MASSACHUSETTS.

FABRIC HAVING THICKENED MOCK SEAMS.

1,267,127.

Specification of Letters Patent.

Patented May 21, 1918.

Application filed August 1, 1916. Serial No. 112,593.

To all whom it may concern:

Be it known that I, ROBERT W. SCOTT, a citizen of the United States, and resident of Boston, in the county of Suffolk and State 5 of Massachusetts, have invented new and useful Improvements in Fabrics Having Thickened Mock Seams, of which the following is a specification.

This invention relates to the manufacture 10 of thickened wale structures in knit fabrics.

Objects of the invention are to provide for 15 hoisery, gloves or other knit articles or fabrics an element of ornament or use consisting of isolated, raised or thickened wales 20 which lend themselves well to the formation of clock effects and mock-seams in hoisery and underwear, ridges on the backs of gloves, and the like; and to provide for the manufacture of fabrics having such thick- 25ened wales upon the usual instruments, without interfering with the steps employed for making ordinary fabrics. Further objects are to provide a structure of this nature adapted for machine-knit fabrics and capable 30 of being begun and ended at any desired parts of the knit article without interference with the making of the article or the operation of the machine, and to provide a knit structure for this purpose which shall be 35 relatively opaque and dense and which does not weaken the fabric to which it is applied, as well as a method of making said structure. Heretofore twisted or tucked stitches have been employed for some of the uses to which 40 my new fabric is adapted, but such structures necessarily contain fewer stitches or 45 stitches under more strain than the body of the fabric, and for these reasons are weaker under longitudinal stress than the remainder 50 of the fabric. Such structures are little or no thicker than the fabric to which they are applied, and are nearly as transparent as the body fabric, so that a thick or opaque mark in a transparent fabric does not result from 55 their employment.

For the above and other purposes my present invention comprises a mode of interknitting an additional or auxiliary yarn in selected needle wales of the fabric, where- 60 by to increase the number of loops in and increase the strength, opacity and thickness of the selected wales, as well as the new articles of manufacture resulting from practice of my said method.

55 In the accompanying drawings,

Figure 1 is a diagram showing the back or rear face of a fabric with a single thickened wale;

Fig. 2 is a similar view of a fabric having a wider raised or thickened part; 60

Fig. 3 is a similar view illustrating one form of an interrupted or intermittent thickened wale or ridge;

Figs. 4 and 5 are similar views illustrating other forms of intermittent structure; 65

Fig. 6 is a diagram development of the relative movements of yarn-guides and knitting needles illustrating one mode of practising the new method;

Fig. 7 is a diagram in plan illustrating 70 one method of laying the auxiliary or additional yarn in relation to the needles and the body or main yarn; and

Fig. 8 is a fragmentary view of a stocking illustrating an application of the new struc- 75 ture.

Referring to Figs. 1 and 2, the fabric may comprise a base or body B knit of a body-yarn *k* in any usual manner, in which fabric the needle-wales *a* are normal wales having 80 a loop in each successive course 1, 3, 5, etc., extending around or across the full width of the fabric. In a wale or wales *b* selected for thickening, an additional thickening yarn *t* is interknit with a loop of yarn *k* in 85 that wale in each successive course, the loops of the yarn *t* constituting in that wale or those wales *b* only an interleaved course 2, 4, 6, etc., the loops of these additional courses in turn being knit through by the 90 next body course 3, 5, 7, etc.

The additional yarn *t* does not extend across the width of the fabric but is floated behind the wale or wales *b* from course to course in floats *y*, Fig. 1, or *y'*, Fig. 2. 95 Where two or more wales *b* are adjacent, as shown in Fig. 2, loops in the same course of yarn *t* are connected by sinker wales *y'* of said yarn *t*, and the floats *y''* are longer and lie at a greater angle to the horizontal. 100

The special structure in the wales *b* may not be continuous, but may, as shown in Fig. 3, be intermittent or interrupted, as there shown, the fabric having in the wales *b* at course 15 normal loops of the yarn *k* only, the yarn *t* being floated free of the body fabric *y* from the last extra or additional course 14 in said wales of the yarn *t* to the next extra or additional course 17 of the yarn *t*. In some cases, as illustrated in 110

Fig. 4, where the additional yarn t is not interknit in one or more courses 15, 16, the said yarn may be bound in behind one or more of the courses in which it is not interknit as illustrated at c, c in the course 16, the yarn t passing behind the wales b in a float y^4 , and being interknit with the normal loops of yarn k of course 16 at course 17.

In some cases, as illustrated in Fig. 5, 10 knitting of the additional yarn t in extra or interleaved courses 21, 24, 26, etc., may be interrupted or intermitted at one or more courses 22 of the body-yarn k , the yarn t floating at y^6 over the intervening normal 15 course of the body fabric, and being bound in previous to knitting the courses 24, 26, etc., by accompanying the loops of that course, shown as 23, at which it is reentered, the wales b here showing double yarn loops 20 d , in which both the body-yarn k and the additional yarn t are drawn through the previous course loops of the body-yarn k .

The wales b, b may or may not be adjacent as shown, and in some cases I may separate 25 them by one or more normal wales a (not shown) floating the yarn t behind these normal wales.

The structures illustrated in Figs. 3, 4 and 30 5 show on the surface of the fabric a puckered or serrated appearance closely imitating certain forms of sewed stitches.

In each case the longitudinal mark or thickened ridge is adapted to be carried through a section or area of fabric reinforced by an additional yarn s in the usual manner, as shown in Figs. 1, 4 and 8. The additional yarn t being interleaved in its own courses, the stitches containing yarns k and s are not called upon also to contain 35 40 yarn t , except in courses adjacent to courses of the yarn t in the form of the fabric shown in Fig. 5.

I recommend forming the fabrics, of which the several species shown are illustrations 45 only, in the following manner:

Referring now to Fig. 7, the circle n indicates a series of needles adapted to be rotated relatively with respect to a yarn-guide k' for the body-yarn and a yarn guide t' for 50 the additional or thickening yarn. Either the circle of needles or the yarn guides may be the movable element. The usual knitting movements are given the needles in relation to the body-yarn guide k' and body-yarn k . 55 Those needles n' selected to knit the wales b are isolated from the other needles at the time of their passage by the yarn guide t' or the yarn t . The yarn t is so supplied, as by feeding it through an ordinary spring 60 take-up, as to permit it to be drawn off in chords or a diameter of the circle n and to be recovered when the needles n' approach the yarn-guide t' . The effect of this is to wrap the yarn t about the needles n' . 65 The needles n' only are actuated to knit

at about that part of their rotation following the yarn guide t' shown at K^2 , which point may be anywhere between the yarn guide t' and the yarn guide k' .

If a single needle n' only is employed, the 70 result is that indicated at Fig. 1. If two or more needles n' are employed, the construction is of the kind shown in Fig. 2.

The needles n' may be isolated at the neighborhood of the yarn guide t' by advancing them, as at w' , Fig. 6, far enough 75 to clear their latches, if they are latch needles, whereupon these needles only take the yarn t' , and these needles only are retracted at w at the knitting point K^2 , and subsequently advanced to the normal path for all 80 the needles shown at N , so that the needles n' take the yarn k and knit at the main knitting point K' .

When it is desired to intermit the special 85 structure as shown in Fig. 3, the yarn guide t' need not be disturbed, but at the knitting point K^2 the needles n' are moved on the normal line N instead of being advanced and retracted.

In case of fabrics like that shown in Fig. 4, the needles n' may be advanced, as at w' , so as to take the yarn t' , and then not be retracted at w , but be moved thereafter in the normal path N , or remain as elevated at 95 w' , said needles making their usual movement at knitting point K' . Needles so advanced at w' , will have cleared their previous loops, as of the course 15 in Fig. 4, and the new run y^4 of the yarn t will also be 100 placed upon them in position to be cast off upon knitting course 16, Fig. 4, with the result illustrated in said figure.

In the case of the fabric of Fig. 5 or the like, knitting is suspended at knitting point 105 K^2 by not advancing the needles n' sufficiently far to clear their latches, but nevertheless causing them to take the yarn t' . The needles may or may not under these circumstances be depressed at w , but their previous loops of course 22, Fig. 5, will not then be cast off, the yarn t' will remain in their hooks, and said needles will subsequently receive the yarn k for course 23, and both the 110 yarn t and the yarn k will be interknit in the double yarn loops d .

I do not herein claim the invention common to this application and my application Serial No. 112,591—(Letters Patent No. 1,256,834, granted February 19, 1918)—for 120 the genus, of which this disclosure is one species; or common to this application and my application Serial No. 112,592, filed August 1, 1916.

What I claim is:

1. A tubular seamless stocking of fabric having normal courses and wales of a body-yarn and spliced areas formed of said body-yarn reinforced by a splicing-yarn, certain wales thereof only having therein ad- 130

ditional courses of an additional yarn continuous from additional course to additional course and from spliced to unspliced areas.

2. A tubular seamless stocking having 5 normal courses and wales of a body-yarn, certain wales thereof only having therein additional courses of an additional yarn continuous from additional course to additional course, said certain wales having at 10 intervals normal loops of the body-yarn interknit with the body-yarn, whereby to form an intermittent mock-seam.

3. A knit fabric having therein knit loops of a body-yarn in all its wales and all its 15 course, said fabric having certain adjacent needle-wales in which successive knit loops are of said body-yarn and of said body-yarn and an additional yarn knit together, said additional yarn extending from one of 20 said certain needle-wales to another and behind the body-yarn loops in said wales in free floats or runs, to form a longitudinally extending thickened mark imitating a looper-sewed seam.

25 4. The art of knitting comprising forming a seamless stocking on an endless series of instruments of a body-yarn interknit in a plurality of wales, interknitting with loops of the body-yarn in certain wales only 30 loops of an additional yarn, knitting a course of body-yarn in all of said wales, and thereafter knitting other loops in said certain wales only of said additional yarn, whereby to form in said certain wales a 35 thickened mock seam in which are loops of said additional yarn intervening between the courses of body-yarn, and runs or floats of the additional yarn extending in the direction of the wales to thicken and render 40 opaque the said mock seam.

5. The art of knitting on a closed series of hooked needles seamless fabrics having certain wales only thickened and projected from the body of the fabric comprising 45 forming of a body-yarn at each of the series of needles a course of stitches, passing an additional yarn into the hooks of two or more selected needles only, casting off the body-yarn loops at said needles only, 50 whereby to knit loops of the additional yarn at said needles only, thereafter forming on

all of the needles a course of loops of the body-yarn only, and thereafter passing said additional yarn behind said selected needles and again into their hooks, said additional 55 yarn being under tension of a spring take-up, and repeating said remaining operations in the same order.

6. The art of knitting on a closed series of hooked needles such as a circular knitting 60 machine, seamless tubular fabrics having certain wales only thickened and projected from the body of the fabric comprising forming of a body-yarn at each of the series of needles a course of stitches, isolating 65 from said series and passing a run of an additional continuous yarn into the hooks of one or more selected needles only, casting off the body-yarn loop, at said isolated needle or needles only, whereby to knit a 70 loop or loops of the continuous additional yarn at said isolated needle or needles only, and thereafter forming on all of the needles a course of loops of the body-yarn, the operation including causing the continuous 75 additional yarn to pass behind said selected needle or needles and into its or their hook or hooks preparatory to repeating the said operations, whereby to form floats extending lengthwise of the fabric. 80

7. The art of knitting stockings having a mock seam characterized by an intermittent thickened wale or wales comprising knitting a body-yarn in normal courses and wales on a series of needles, forming of an 85 additional continuous yarn a course of loops in one or more selected wales only by operating the needles of said wales to knit after laying upon them said additional yarn, thereafter knitting the body-yarn normally in all of the wales, repeating said 90 operations for a predetermined number of courses, and thereafter causing two or more successive normal courses to be formed in all the wales during a relation of said selective needles and additional yarn inoperative to cause the additional yarn to be 95 formed into knit loops.

Signed by me at Boston, Massachusetts, this twenty-ninth day of July, 1916.

ROBERT W. SCOTT.
